US0D1032927S

(12) **United States Design Patent** (10) Patent No.: **US D1,032,927 S**
(45) Date of Patent: ** Jun. 25, 2024

(54) **VAPORIZER DEVICE**(71) Applicant: **JUUL Labs, Inc.**, San Francisco, CA (US)(72) Inventors: **Adam Bowen**, San Mateo, CA (US); **James Monsees**, San Francisco, CA (US); **Steven Christensen**, Burlingame, CA (US); **Joshua Morenstein**, San Francisco, CA (US); **Christopher Nicholas HibmaCronan**, Oakland, CA (US)(73) Assignee: **Juul Labs, Inc.**, Washington, DC (US)(**) Term: **15 Years**(21) Appl. No.: **29/774,165**(22) Filed: **Mar. 15, 2021****Related U.S. Application Data**

(63) Continuation of application No. 29/707,225, filed on Sep. 26, 2019, now Pat. No. Des. 913,579, which is a continuation of application No. 29/650,601, filed on Jun. 7, 2018, now Pat. No. Des. 861,975, which is a continuation of application No. 35/001,169, filed on Jul. 28, 2016 (U.S. filing date under 35 U.S.C. 384), and having an international filing date of Mar. 11, 2016, now Pat. No. Des. 825,102.
